Inventor
Robert A. Kennedy

Watson E. Coleman
Atty

UNITED STATES PATENT OFFICE.

ROBERT A. KENNEDY, OF LAVONIA, GEORGIA.

WRENCH.

Application filed January 7, 1924. Serial No. 684,832.

To all whom it may concern:

Be it known that I, ROBERT ARCHIE KENNEDY, a citizen of the United States, residing at Lavonia, in the county of Franklin 5 and State of Georgia, have invented certain new and useful Improvements in Wrenches, of which the following is a specification, reference being had to the accompanying drawings.

10 This invention relates to certain improvements in wrenches and it is an object of the invention to provide a novel and improved device of this general character comprising a movable jaw together with means automatically operating to move said jaw into set position.

15 It is also an object of the invention to provide a novel and improved wrench wherein is employed a locking element for holding the movable jaw in various positions.

20 The invention consists in the details of construction and in the combination and arrangement of the several parts of my improved wrench whereby certain important advantages are attained and the device rendered simpler, less expensive and otherwise more convenient and advantageous for use, as will be hereinafter more fully set forth.

25 The novel features of my invention will hereinafter be definitely claimed.

30 In order that my invention may be the better understood, I will now proceed to describe the same with reference to the accompanying drawings, wherein:—

35 Figure 1 is a view partly in elevation and partly in section illustrating a wrench constructed in accordance with an embodiment of my invention;

40 Figure 2 is an elevational view of the wrench as herein disclosed;

45 Figure 3 is a sectional view taken substantially on the line 3—3 of Figure 2.

As disclosed in the accompanying drawings, 1 denotes a shank of the wrench provided at its outer end with the stationary jaw 2. The opposite end portion of the shank 1 is suitably secured to the handle or hand grasp 3 the same being detachably engaged with a casing C.

50 The casing C is substantially U-shaped in cross section as is illustrated in Figure 3, and has its lower or outer end portion closed by the plate 4. The plate 4 is provided with an opening 5 through which the end portion of the handle or hand grasp 3 is disposed, said extremity

being in threaded engagement with a washer 6. This washer 6 is insertible within the casing C and has direct contact with the inner face of the plate 4, said washer 6 being also received within a groove or channel 7 formed in the inner walls of the casing C immediately adjacent to the plate 4.

55 Freely mounted upon the shank 1 outwardly of the casing C is the movable jaw 8, said jaw being provided with an inwardly disposed rod 9 spaced from the shank 1 and in parallelism therewith. This rod 9 is slidably engaged within an opening 10 provided in the casing C and with which is adapted 60 to engage the holding member 11.

65 The holding member 11 is slidably arranged within the opening 12 disposed transversely of the casing C and intersecting the opening 10, said member 11 being 70 provided in a marginal portion thereof with a recess 14 in which is received the rod 9. One end portion of the holding member 11 is pivotally engaged, as at 15, with an operating lever 16 substantially housed within 75 a groove or channel 17 in a side face of the casing C. The lever 16 has its inner end portion pivotally connected, as at 18, with the casing C.

80 Interposed between the opposite end portion of the lever 16 and the base of the groove or channel 17 is an expansible member 19 preferably a coil spring which serves to constantly urge a wall of the recess 14 of the member 11 into close contact with the 85 rod 9 whereby the jaw 8 is held against movement lengthwise of the shank 1. The outer end portion of the lever 16 is provided with a finger piece 20 and upon depressing said outer end portion of the lever 16, the 90 member 11 is free from the rod 9 whereby 95 the jaw 8 is readily movable along the shank 1.

95 The jaw 8 is constantly urged toward the 100 jaw 2 through the instrumentality of the expansible member 21 herein disclosed as a coil spring encircling the shank 1 and interposed between the jaw 8 and the connected end portion of the handle member or hand grip 3.

105 When the holding member 11 is in release position the spring 21 serves to automatically move the jaw 8 toward the jaw 2 and which is of particular advantage to assure a ready and quick setting of the wrench with 110 respect to its work.

From the foregoing description it is

thought to be obvious that a wrench constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

15 I claim:—

1. A wrench comprising a shank having a jaw, a casing operatively engaged with the shank, said casing having an opening to one side of the shank and in parallelism therewith, a jaw slidably engaged with the shank, means for automatically moving the second named jaw toward the first named jaw, a rod carried by the second named jaw and slidably engaged within the opening in the casing, said casing having a second opening disposed transversely thereof and intersecting the first named opening, a member slidably engaged within the second named opening and provided in a marginal portion with a recess in which is received a rod, a lever arranged exteriorly of the casing and having one end portion pivotally engaged with the casing adjacent the inner end thereof, said lever being of a length to extend beyond the outer end of the casing, means for pivotally connecting the member and the lever, and means for constantly urging the lever in one direction to maintain the member in holding engagement with the rod, the casing being provided with a channel in which the lever is substantially housed.
- 20 2. A wrench comprising a shank having a jaw, a casing operatively engaged with the shank, said casing having an opening to one side of the shank and in parallelism therewith, a jaw slidably engaged with the shank, means for automatically moving the second named jaw toward the first named jaw, a rod carried by the second named jaw and slidably engaged within the opening in the casing, said casing having a second opening disposed transversely thereof and intersecting the first named opening, a member slidably engaged within the second named opening and provided in a marginal portion with a recess in which is received a rod, a lever arranged exteriorly of the casing and having one end portion pivotally engaged with the casing adjacent the inner end thereof, said lever being of a length to extend beyond the outer end of the casing, means for pivotally connecting the member and the lever, and means for constantly urging the lever in one direction to maintain the member in holding engagement with the rod.
- 25 3. A wrench comprising a shank provided with a jaw, a casing substantially U-shaped in cross section having its outer end closed by a plate, said plate being provided with an opening, the shank being disposed through the casing and through the opening in the plate, a hand grasp for the shank, an end portion of said hand grasp being disposed through the opening in the plate, a washer in threaded engagement with said end portion of the hand grasp and in contact with the inner face of the plate, the inner walls of the casing being provided with a groove in which said washer is received, and a movable jaw mounted on the shank between the casing and the jaw of the shank.

therewith, a jaw slidably engaged with the shank, means for automatically moving the second named jaw toward the first named jaw, a rod carried by the second named jaw and slidably engaged within the opening in the casing, said casing having a second opening disposed transversely thereof and intersecting the first named opening, a member slidably engaged within the second named opening and provided in a marginal portion with a recess in which is received a rod, a lever arranged exteriorly of the casing and having one end portion pivotally engaged with the casing adjacent the inner end thereof, said lever being of a length to extend beyond the outer end of the casing, means for pivotally connecting the member and the lever, and means for constantly urging the lever in one direction to maintain the member in holding engagement with the rod, the casing being provided with a channel in which the lever is substantially housed.

3. A wrench comprising a shank provided with a jaw, a casing substantially U-shaped in cross section having its outer end closed by a plate, said plate being provided with an opening, the shank being disposed through the casing and through the opening in the plate, a hand grasp for the shank, an end portion of said hand grasp being disposed through the opening in the plate, a washer in threaded engagement with said end portion of the hand grasp and in contact with the inner face of the plate, the inner walls of the casing being provided with a groove in which said washer is received, and a movable jaw mounted on the shank between the casing and the jaw of the shank.

In testimony whereof I hereunto affix my signature.

ROBERT A. KENNEDY.
